UNITED STATES PATENT OFFICE

2,640,438

OUTLET ASSEMBLY FOR HOPPER-TYPE
RAILWAY CARS

George B. Dorey, Westmount, Quebec, Canada;
assignor to Enterprise Railway Equipment
Company, Chicago, Ill., a corporation of Illinois

Application August 24, 1949, Serial No. 112,032

10 Claims. (Cl. 105—282)

1

This invention relates, generally, to railway cars of the hopper type, and it has particular relation to the construction of outlet assemblies therefor.

Among the objects of this invention are: To provide a weatherproof construction for discharge outlet assemblies for hopper-type railway cars; to extend three of the four walls which define the hopper opening below the gate which closes the opening; to provide a frame at the hopper opening on which the gate is slidably mounted with three of the four hopper walls telescoped over the corresponding sides of the frame; to form the frame of Z-shaped members with the upper flange extending inwardly to provide a runway for slidably supporting the gate and the lower flange extending outwardly for attachment to a removable chute; to construct the gate for use with a single pinion adapted to engage a rack located centrally of the underside of the gate; to provide the gate with a laterally opening recess on three sides for receiving a compressible gasket; to proportion the entrance to the recess so that the gasket must be compressed to enter or leave the recess; and to provide a latch mechanism for the gate which can be assembled as a unit with the frame and arranged to hold the gate in the closed position.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a view, in side elevation, of the form of hopper for a railway car with which the present invention is particularly adapted to be used;

Figure 2 is a view, similar to Figure 1, but showing the outlet assembly constructed in accordance with this invention assembled with the hopper;

Figure 3 is a view, in front elevation, of the hopper and outlet assembly shown in Figure 2;

Figure 4 is a top plan view of the outlet assembly detached from the hopper;

2

Figure 5 is a detail sectional view, at an enlarged scale, taken along the line 5—5 of Figure 4;

Figure 6 is a view, somewhat similar to Figure 5, and showing the gate in the closed position;

Figure 7 is a detail sectional view, at an enlarged scale, taken along the line 7—7 of Figure 4;

Figure 8 is a bottom plan view of the gate;

Figure 9 is a view, in end elevation, of the gate shown in Figure 8;

Figure 10 is an enlarged sectional view showing how the gasket must be compressed so as to enter the recess therefor which is provided along three sides of the gate; and

Figure 11 is a view of a portion of the tubular gasket and showing how it is cut away at the section where it bends around the corner of the gate.

20 Referring now particularly to Figures 1, 2, and 3 of the drawings, it will be observed that the reference character 10 designates, generally, a four-sided hopper which has inclined floor sections 11, 12, 13, and 14 for directing lading contained therein to an opening in the bottom which is defined, in part, by three vertical hopper wall portions 15, 16, and 17. The vertical hopper wall portions 15, 16, and 17 telescope with or extend over an outlet assembly, shown generally at 18, which may be held in place by rivets 19 or by welding or both. It will be noted that the wall portions 15, 16, and 17 extend over the outlet assembly 18 and that there is no joint therebetween opening upwardly outside of the hopper 10. Rain, sleet, snow, etc., beating against the sides of the hopper 10 does not lodge against an upper portion of the outlet assembly located outside of the hopper 10, as in prior constructions, and thus a more weathertight construction is provided when the present invention is employed.

40 The details of construction of the hopper assembly are shown more clearly in Figures 4, 5, 6, and 7 of the drawings. It will be observed that it is formed of a generally U-shaped cast-iron frame 20 which has parallel sides, shown generally at 21 and 22, interconnected by an end 23. The sides 21 and 22 and the end 23 each have a Z-shaped section. For example, as shown in Figure 7, the sides 21 and 22 have respectively a central vertical section 25 and 26, an upper inwardly extending flange or shelf 27 and 28, and a lower flange or wall 29 and 30 which extends outwardly to provide for receiving a removable supplemental chute in a manner to be described presently. Likewise, as shown in 50 Figure 5, the end 23 has a central vertical section

31, a flange or shelf 32 extending inwardly, and an outwardly extending flange or wall 33. It will be understood that each Z-shaped side 21 and 22 and the end 23 are cast as an integral unit and that the central vertical sections thereof constitute a three sided frame having the upper flanges or shelves extending inwardly therefrom and the lower flanges or walls extending outwardly.

Opposite the end 23, as shown in Figure 5, there is an end member 35 which is welded between the central vertical sections 25 and 26 of the sides 21 and 22. The end member 35 has an inclined wall 36 which constitutes an extension of the floor section 14. Also it has a horizontal wall 37 which defines the lower portion of an opening through which a gate (identified hereinafter) moves to close the opening through the hopper 10.

Underneath the inclined wall 36 of the end member 35 is a bracket 38 which may be held in place by rivets 39. The bracket 38 has a horizontal flange 40 which is arranged to receive a flange of a removable supplemental chute for holding the same in operative position underneath the hopper 10. For a similar purpose a U-shaped clamp member 42, Figures 3, 4, and 7, is provided and secured by rivets 43 to a projecting portion 44 of the flange or wall 30. It will be observed that the upper arm of the U-shaped clamp member bears against the upper side of the projecting portion 44 while the lower arm is spaced therefrom for receiving thereabove the flange of the removable supplemental chute. Other portions of the chute bear against the underside of the flange or wall 29 and 33 which have projecting portions 45 and 46 for receiving C-clamps to hold the supplemental chute in position as will be understood readily by those skilled in the art.

As illustrated in Figures 2 and 5 of the drawings, the central vertical sections 25 and 26 of the sides 21 and 22 are provided with extensions 47 and 48, respectively, which extend upwardly underneath the inclined floor section 14 and are shaped to receive an angle 49 which preferably is secured thereto by welding. It will be observed that the longer flange of the angle 49 extends underneath the inclined floor section 14 and serves to support the same.

It will be observed that a rectangular opening 50 is defined in part by the horizontal wall 37 of the end member 35 and the lower edges 51 and 52 of the longer flange of the angle 49 and the lower edge of the inclined floor section 14 through which a gate, shown generally at 53, can be moved to close the opening at the bottom of the hopper 10. It will be observed that the gate 53 has a flat upper surface 54, beveled sides 55 and 56 and a beveled front edge 57. As shown more clearly in Figure 8 of the drawings, bearing surfaces 59 and 60 are machined along the undersides of the gate 53 and are arranged to engage machined bearing surfaces 61 and 62 which are provided on the upper sides of the flanges or shelves 27 and 28, Figure 7. In like manner a bearing surface 64 is machined along the underside of the gate 53 near the forward end for engaging a corresponding bearing surface 66 on the upper side of the flange or shelf 32, Figure 5. These bearing surfaces, being carefully machined, in part provide means for sealing the opening through the hopper 10 when the gate 53 is in the closed position as shown in Figure 6. Addi-

tional sealing means is provided as will be described in detail hereinafter.

As illustrated more clearly in Figure 8 of the drawings the underside of the gate 53 is provided with integrally formed depending ribs 71, 72, 73, and 74 which extend in the direction of movement of the gate. The depending ribs 71 and 72 define a side panel 75 while the depending ribs 73 and 74 define another side panel 76. Transverse ribs 77 extend between the ribs 71 and 72 in panel 75 and between the ribs 73 and 74 in panel 76 to provide added strength for the gate 53. In addition, transverse ribs 78 and 79 extend along the rear and front edges of the gate 53 as illustrated. It will be observed that the ribs 71 and 74 are not parallel to the edges of the gate 53 but rather that they are inclined with respect thereto, being further apart near the rear edge of the gate 53 than they are at the forward edge.

20 The purpose for this will be apparent presently.

With a view to providing additional sealing means for the gate 53 when it is in the closed position, a tubular gasket 82 is provided in a recess 83, Figure 10, which extends around three sides 25 of the gate 53. The tubular gasket 82 is formed of compressible material such as a rubber hose and the construction of the recess 83 and the entrance thereto is such that the gasket 82 must be compressed, as shown in Figure 10, in order to enter or leave the recess 83. It will be observed that the recess 83 is formed in part by the bearing surface 60 and by an indented portion 84 immediately in back of this bearing surface. The rear wall of the recess 83 is formed by the depending rib 74 and the bottom wall is formed by the upper surface of a plate 85 which is secured to each of the panels 75 and 76 by welding as indicated at 86. Slots 87 are provided, as shown, in the outer edges of the plates 85 for facilitating the entrance and removal of the tubular gasket 82 into and out of the recess 83 and also to permit the welding along the ribs 71 and 74.

When the gate 53 is in the fully closed position, the outermost surface of the gasket 82 engages inner surfaces 89 and 90 of the flanges or shelves 27 and 28, Figure 7. These surfaces 89 and 90 are spaced furthest apart at the open end of the frame 20, Figure 4, and are closest together along the other closed end so as to define a wedge shaped opening the sides of which are parallel to the depending ribs 71 and 74 which, as previously described, are also similarly inclined. In the closed position the gasket 82 is compressed between the outer surfaces of the ribs 71 and 74 and the inner surfaces 89 and 90 of the flanges or shelves 27 and 28.

The portion of the tubular gasket 82 along the front edge of the gate 53 is arranged to engage the inner surface 92 of the flange or shelf 32 as shown more clearly in Figure 6. It will be noted that the tubular gasket 82 here is compressed between the forward surface of the transverse rib 79 and the inner surface 92 of the flange or shelf 32 when the gate 53 is closed.

65 With a view to facilitating the bending of the tubular gasket 82 around the corners of the gate 53 at the junctions between the rib 79 and the ribs 71 and 74, it is cut away or slotted as indicated at 93 in Figure 11. This construction prevents bunching of the tubular gasket 82 at these portions thereof.

As shown in Figure 7 more clearly, the outside edges of the plates 85 underlie the flanges or shelves 27 and 28. The purpose of this construction is to prevent the gate 53 from being lifted

bodily off of the bearing surfaces 61 and 62 when the car is empty.

Referring again to Figure 8 of the drawings, it will be observed that the reference character 95 designates, generally, a central panel between the side panels 75 and 76. The central panel has the depending ribs 72 and 73 along its sides and there between extend rack teeth 96 which serve to provide additional reinforcement for the gate 95. In addition, the rack teeth 96 are arranged to engage a pinion 97; Figure 5, for moving the gate 53 to and from the closed position. The pinion 97 is fast on a shaft 98 which extends transversely through the central vertical sections 25 and 26 of the sides 21 and 22. The ends of the shaft 98 are journaled in trunnions 99 and 100 which are formed integrally with the sides 21 and 22; Figure 7. As here shown, a sleeve 101 is secured by a bolt or pin 102 to one end of the shaft 98 for holding it in position. Any suitable head can be applied to the other end of the shaft 98 adjacent the trunnion 99 for rotating it to rotate the pinion 97 and move the gate 53 to and from the closed position.

As shown in Figure 4 of the drawings, rearwardly extending projections 103 and 104 are provided for the sides 21 and 22 of the frame 20. Their cross section is the same as described for the sides 21 and 22 as shown in Figure 7. The purpose of the rearwardly extending projections 103 and 104 is to provide for supporting the gate 53 in the open position as shown in Figure 5.

It will be recalled that the plates 85, Figure 9, project below the undersurface of the gate 53. In order to accommodate the plates 85, the horizontal wall 37 of the end member 35 is depressed as indicated at 105 in Figures 5 and 7.

The preferred form of latch mechanism for holding the gate 53 in the closed position is indicated, generally, at 108. This latch mechanism is a unitary latch mechanism and can be assembled as a unit and applied to the frame 20 in the manner to be described.

The unitary latch mechanism 108 comprises brackets 109 which may be secured by rivets 110 to the rearwardly extending portions 103 and 104 of the sides 21 and 22. The brackets 109 have upstanding bearing portions 111 to which inside and outside links 112 and 113 are pivoted by means of rivets 114, Figures 4, 5, and 6. Arms 115 and 116 are pivoted by rivets 117 between the outer ends of the links 112 and 113. A bodily movable locking shaft 118 extends between the arms 115 and 116. The locking shaft 118 can be moved manually by means of a handle 119 which is formed integrally with the arm 116. The locking shaft 118 is arranged to interfit with a transverse recess 120, Figure 5, which extends along the rear edge of the gate 53. The locking engagement of the shaft 118 and the recess 120 is illustrated more clearly in Figure 6 where the gate 53 is shown in the closed position. In order to facilitate the movement of the shaft 118 bodily out of locking engagement with the recess 120 and to a position above the gate 53, an inclined surface 121 is provided on each of the brackets 109. As torque is applied to the handle 119 to swing the shaft 118 bodily in a clockwise direction about the rivets 117, the shaft 118 rides up the inclined surfaces 121 and thus is moved to a position above the gate 53 and out of the path of the forward wall of the recess 120. As shown in Figure 5 the locking shaft 118 is held in the unlocked posi-

tion so that the gate 53 can be moved from the closed position shown in Figure 6 to the open position shown in Figure 5.

Any suitable means can be provided for locking the shaft 118 in the position where it holds the gate 53 closed. For example, a bolt 122, Figure 6, can be provided and slidably mounted within the shaft 118 which is hollow. The bolt 122 can be moved by a handle 123, Figure 4, which projects from the bolt 122 outwardly through a slot 124 in the shaft 118. At its outer end the bolt 122 has flanges 125 extending radially therefrom which are arranged to project through a correspondingly shaped opening 126 in the outside link 113. A slot 127, Figure 4, in one of the flanges 125 is provided for receiving a conventional seal so as to prevent unauthorized movement of the bolt 122, as will be understood readily.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a railway car hopper construction, in combination, a four sided hopper defining a discharge opening and comprising floor sections extending downwardly for directing lading from the car body to said opening; a gate slidably mounted beneath one of the sides of said hopper for closing said opening; the three remaining sides of said hopper forming a skirt and extending uninterruptedly below said gate, and shelves extending laterally inwardly from said three sides in supporting relation to said gate; said three sides of said hopper defining an integral weatherproof enclosure around the corresponding three sides of said gate having no upwardly opening joint likely to permit entrance of water and contamination of the lading in the hopper.
2. In a railway car hopper construction, in combination, a foursided hopper defining a discharge opening and comprising floor sections extending downwardly for directing lading from the car body to said opening; a gate slidably mounted beneath one of the sides of said hopper for closing said opening; the three remaining sides of said hopper forming a skirt and extending uninterruptedly below said gate, and a frame structure having vertical wall sections secured to the inner surfaces of said three sides with shelves extending laterally inwardly from said wall sections to slidably support said gate, said three sides of said hopper defining an integral weatherproof enclosure around the corresponding three sides of said gate having no upwardly opening joint likely to permit entrance of water and contamination of the lading in the hopper.
3. In an outlet assembly for a load containing hopper having a foursided discharge opening and a horizontally sliding gate for closing said opening, in combination, downwardly inclined floor sections in said hopper for directing lading to said opening, three of said floor sections having portions forming a skirt extending uninterruptedly downwardly vertically below said gate, and shelves extending laterally inwardly from said vertical portions of said floor sections in supporting relation to said gate, said portions of said three floor sections defining an integral weatherproof enclosure around the correspond-

ing three sides of said gate having no upwardly opening joint likely to permit entrance of water and contamination of the lading in the hopper.

4. In an outlet assembly for a load containing hopper having a four sided discharge opening and a horizontally sliding gate for closing said opening, in combination, downwardly inclined floor sections in said hopper for directing lading to said opening, three of said floor sections having portions forming a skirt extending uninterruptedly downwardly vertically below said gate, and a frame structure having vertical wall sections secured to the inner sides of said vertical portions with shelves extending laterally inwardly from said wall sections to slidably support said gate, said portions of said three floor sections defining an integral weatherproof enclosure around the corresponding three sides of said gate having no upwardly opening joint likely to permit entrance of water and contamination of the lading in the hopper.

5. In an outlet assembly for a load containing hopper having a four sided discharge opening and a correspondingly shaped sliding gate for closing said opening, a frame surrounded on three sides by three of the four sides defining said discharge opening and carried by said hopper for supporting said gate on three sides in its closed position, the gate supporting sides of said frame being of Z shape with the upper flange thereof underlying said gate and the lower flange underlying said three sides of said hopper, said three sides of said hopper defining an integral weatherproof enclosure around the corresponding three sides of said frame and gate having no upwardly opening joint likely to permit entrance of water and contamination of the lading in the hopper.

6. In an outlet assembly for a load containing hopper having a four sided discharge opening and a correspondingly shaped sliding gate for closing said opening, a frame surrounded on three sides by three of the four sides defining said discharge opening and carried by said hopper for supporting said gate on opposite sides thereof, the gate supporting sides of said frame being of Z shape and extending lengthwise of the direction of movement of said gate with the upper flanges of said sides extending inwardly toward each other and constituting runways for said gate and the lower flanges of said sides extending outwardly and underlying the corresponding sides of said hopper, said three sides of said hopper defining an integral weatherproof enclosure around the corresponding three sides of said frame and gate having no upwardly opening joint likely to permit entrance of water and contamination of the lading in the hopper.

7. In an outlet assembly for a load containing hopper having a four sided discharge opening and a correspondingly shaped sliding gate for closing said opening, a frame surrounded on three sides by three of the four sides defining said discharge opening and carried by said hopper for supporting said gate on opposite sides thereof and at one end in its closed position, the gate supporting sides and end of said frame being of Z shape with the upper flange of each underlying said gate and the lower flange of each underlying the corresponding sides of said

hopper, said gate supporting sides of said hopper extending beyond said opening away from said end of said frame to support said gate in its open position, said three sides of said hopper defining an integral weatherproof enclosure around the corresponding three sides of said frame and gate having no upwardly opening joint likely to permit entrance of water and contamination of the lading in the hopper.

10 5. In a discharge outlet for a hopper comprising, in combination, a four sided frame defining the hopper opening, and a gate slidably mounted on said frame for closing said opening, said gate being reinforced on its underside by depending ribs extending lengthwise in the direction of movement of said gate and spaced from each other transversely of said direction of movement thereby providing side panels and a central panel each of substantial width, said central panel having rack teeth extending between said longitudinal ribs, and plate members underlying said side panels and extending between the ends of said rack teeth and the sides of said gate.

20 9. A rectangular sliding gate for closing the opening of a discharge hopper, said gate along three sides underneath having a horizontal bearing surface, a resilient laterally compressible tubular gasket extending adjacent said surface, and a chambered portion for receiving and holding said gasket, said chambered portion including an indented portion above the plane of said bearing surface and adjacent thereto, a vertical wall adjacent said indented portion and spaced from said bearing surface, and a plate section 30 extending laterally from the lower margin of said vertical wall to underlie said bearing surface and spaced therefrom to provide an opening leading to said chambered portion the width of which is less than the diameter of said gasket thereby necessitating compression of said gasket on insertion or removal thereof.

40 10. A sliding gate for a four sided discharge opening of a load containing hopper, said gate along three sides underneath having a horizontal bearing surface for cooperation with a supporting surface on said hopper, and a compressible tubular gasket adjacent said bearing surface for cooperation with downwardly extending faces on said hopper adjacent said supporting surface, said gasket being retained in an open-sided recess in said gate the open side of which has a width less than the diameter of said gasket thereby necessitating compression of said gasket on insertion or removal thereof.
